CLAIM

The ornamental design for a straw holder, as shown.

DESCRIPTION

FIG. 1 is a perspective view of a straw holder showing my new design.

FIG. 2 is a side elevational view thereof.

FIG. 3 is a side elevational view thereof showing the side opposite that seen in FIG. 2.

FIG. 4 is a side elevational view as seen from the left-hand portion of FIG. 2.

FIG. 5 is a side elevational view as seen from the right-hand portion of FIG. 2.

FIG. 6 is a top plan view thereof; and,

FIG. 7 is a bottom plan view thereof.
